UNITED STATES PATENT OFFICE

LOUIS SCHUMM, 3D, OF LA PORTE, INDIANA, ASSIGNOR TO SUPERIOR WOOD PRODUCTS CORPORATION, OF LA PORTE, INDIANA, A CORPORATION OF INDIANA

STORE COUNTER

Application filed August 15, 1930. Serial No. 475,541.

This invention appertains to store furniture and more particularly to an improved counter for use in dry goods and like stores.

One of the primary objects of my invention is to provide a store counter which can be shipped in a more or less knocked-down condition and can be readily assembled and which will present an attractive and pleasing appearance to the trade.

Another important object of my invention is to provide a store counter which will be durable and efficient in use, one that will be simple and easy to manufacture, and one which can be placed upon the market at a small cost.

A further salient object of my invention is to provide a store counter which can be made in any desired number of sections so that the same can run a desired length of a store.

A further object of my invention is the provision of novel means for forming sections of the counter whereby a rigid and substantial structure will be had when the sections are connected together, the counter in its set up condition providing ample space for both display and storage purposes and embodying conveniences for facilitating the waiting on of customers.

Another important object of my invention is the provision of upper and lower shelves arranged in a novel manner in the counter which serve as means for bracing the counter longitudinally and as means for receiving goods for storage purposes and as means for receiving wrapping and bag material for goods sold.

With these and other objects in view, the invention consists in the novel construction, arrangement and formation of parts, as will be hereinafter more specifically described, claimed, and illustrated in the accompanying drawings, in which drawings:—

Figure 1 is a front elevation of my improved counter showing parts thereof broken away and in section.

Figure 2 is a rear elevation of my improved counter.

Figure 3 is a top plan view of my improved counter showing parts of the serving top

broken away to illustrate the arrangement of the upper service shelf with the compartments for the paper bags, wrapping paper, twine drawer, and wrapping slide.

Figure 4 is a fragmentary perspective view of a portion of my improved counter in its set up condition looking toward one end thereof and illustrating the novel arrangement of one of the intermediate transverse supporting frame members and the arrangement of the upper service shelf and the lower storage shelf.

Figure 5 is a fragmentary perspective view showing a portion of the frame prior to the association of the panels, shelves and tops therewith.

Figure 6 is a fragmentary detail perspective view looking toward one end illustrating the counter in a partly set up condition prior to the association of the front panels and top therewith, and illustrating the arrangement of the upper service shelf and the lower storage shelf and one end panel.

Figure 7 is a detail sectional view illustrating the means employed for connecting the sections of the improved counter together.

Referring to the drawings in detail, wherein similar reference characters designate corresponding parts throughout the several views, the letter A generally indicates my improved counter which comprises a base frame 10 which includes a front longitudinally extending rail 11, end rails 12 and intermediate transverse rails 13. The intermediate transverse rails 13 preferably have their lower faces cut away as at 14 to define feet 15. The front rail 11 and the end rails 12 have secured thereto in any desired way finishing strips or plates 16 and 17, the upper edges of which extend above the front rail 11 and the end rail 12 to form a seat or rabbet 18, for a purpose, which will be later described. The front lower edges of the front and end finishing strips 16 can be provided with quarter round molding 18 to add to the finished appearance thereof. The rear edges of the end and intermediate rails 12 and 13 are connected together by rear finishing longitudinally extending strips 20 which can be

dispensed with if desired. It is to be also noted that the intermediate rails 13 of the base terminate short of the upper edges of the front and rear finishing strips 16 and 20 and that the front finishing strips 16 directly in front of each intermediate rail 13 is provided with a notch 21 which extends from the upper edge of the front finishing strips to a point in alignment with the upper edge of the intermediate rails 13. The intermediate rails 13 provide supports for the transverse frames or standards 22, which are built as units and these transverse supporting frames or standards include front and rear posts 23 and 24, a top connecting piece or rail 25 and an intermediate brace rail 26 arranged in spaced parallel relation to the top rail or piece 25. The front edge of the front post 23 is provided with a longitudinally extending rib 27 which is spaced equidistantly from the opposite faces of the sides of the frame and the lower end of this rib is received within the notches 21 as clearly shown in Figure 5 of the drawings.

By the construction so far, it can be seen that the ends of the posts 23 and 24 rest on the upper faces of the transverse rails 13 with the outer faces thereof in abutting engagement with the inner faces of the finishing rear and front strips 20 and 16.

Arranged in parallel relation with the transverse frames 22 are end panels 30 which are built in units and the lower edges of the panels are received in the seat or rabbet 18 defined by the upper edges of the end rails 12 and inner faces of the end finishing strips 17. The end edges of the end panels 30 abut against the inner faces of the front and rear finishing strips 16 and 20. The inner faces of the end panels 30 are provided with cleats 31 which are in horizontal alignment with the intermediate cross pieces 26 of the transverse frames or standards 22.

Between the end panels and adjacent the intermediate transverse frames 22 and between each pair of intermediate transverse frames 22 are arranged the front panels 32, which are also built in units and these panels have their lower edges resting in the seat or rabbet 18 defined by the longitudinal rail 11 and the front finishing strips 16. It is to be noted that the inner edges of the front panels 32 engage the front edges of the transverse frames 22 on each side of the vertical ribs 27 thereof. The front panels 32 and the end panels 30 are held in place by the lower storage shelf 33 and the upper service shelf 34. The lower storage shelf 33 is placed in position with its lower face resting on the transverse intermediate rails 13 and the end rails 12, and this shelf has its front and rear edges notched as at 35 for receiving the front and rear posts 23 and 24 of the transverse frames or standards 22. The front edge of the lower storage shelf 33 rests on the upper

edge of the front rail 11 and abuts against the front panels 32 adjacent to the lower ends thereof. It will thus be noted that the front panels are received between the upper edge of the front strips 16 and the front edge of the storage shelf 33 and rests on the upper surface of the front rail 11. Likewise the ends of the storage shelf rests on the upper surface of the end rails 12 in spaced relation to the finishing end strips 17 and rests against the inner faces of the end panels 30 at the lower edges thereof. The intermediate pieces 26 of the transverse frames or standards and the cleats 31 receive the upper or service shelf 34 and the front and rear edges of this service shelf is notched as at 36 to receive the front and rear posts 23 and 24 of the transverse frames 22 and this shelf 34 also engages the front panels 33 and the end panels 30. Thus these panels are firmly held in place. The end panels 30 and the front panels 32 can be connected with the lower shelf 33 by means of angle brackets 37.

In order to add a finished appearance to the front of the counters and to firmly hold the counter in assembled condition ornamental molding strips 38 are secured to the front panels 32 at the meeting edges thereof and overlie the ribs 27 of the transverse frames or standards 22. Likewise these ornamental moldings 38 can be used at the ends of the counter as shown. The upper rear corner edges of the transverse standards 22 can be notched as at 39 for the reception of an upper rear rail 40 which can be secured in place in any desired way. The upper edges of the transverse frame 22, the front panels 32, the end panels 30, and the rear rail 39 receive the display top 41, which can be constructed in any desired way. As shown, the edges of the top 41 are provided with cornices or moldings 42 which extend above and below the face of the table top. It is to be also noted that the table top 41 extends beyond the front and rear faces of the body portion of the body and that the ornamental front molding strips 38 extend under the table top and likewise forms a support therefor. The lower inner faces of the cornices 42 can rest against the finishing molding strips 38 if desired.

I preferably use the space between the shelf 34 and the table top 41 for service purposes and thus one part of the shelf may be utilized for wrapping paper, another part may be utilized for receiving compartments or pockets 45 of different sizes opening out through the rear of the counter for receiving paper bags. Another portion of this space can receive a slide 45 which can be pulled out to facilitate the wrapping of packages. A suitable drawer 46 can also be provided for the reception of twine, scissors and the like. The lower shelf 33 can be utilized for receiving different kinds of goods.

The rear of the counter is left entirely open as clearly shown in the drawings.

From the foregoing description, it can be seen that I have provided an exceptionally simple and durable form of counter which will possess the maximum amount of utility and which will possess a pleasing and attractive appearance to the eye.

If preferred, the counter can be made in different sections when the counter is of an extreme length and in this instance the top 10 can be made in different sections as well as the shelves 33 and 34. When the sections are joined two of the transverse intermediate 15 rails 13 can be placed in abutting relation and connected by means of suitable bolts 47.

Changes in details may be made without departing from the spirit or the scope of this invention, but:—

20 What I claim as new is:

1. In a store counter, a longitudinally extending base rail, transverse end rails, and intermediate transverse rails, transverse supporting frames seated on the intermediate 25 rails having vertically disposed ribs on the front face thereof located equa-distantly of the side faces of the frames, a front finishing strip connected with the base rail and extending above the upper face thereof and defining 30 in conjunction therewith a seat, front panels having their lower edges received in said seat and their adjacent edges engaging the opposite sides of the rib and the front faces of the transverse frames, and finishing and 35 securing molding strips engaging over the meeting edges of the panels and ribs.

2. In a counter, a longitudinally extending base rail, transverse end rails and intermediate transverse rails, transverse supporting 40 frames seated on the intermediate rails having vertically disposed ribs on the front faces thereof located equa-distantly of the side faces of the frames, a front finishing strip connected with the base rail and extending above the upper face thereof and defining in 45 conjunction therewith a seat, front panels having their lower edges received in said seat and their adjacent edges engaging the opposite sides of the rib and the front faces of the transverse frames, finishing and securing 50 molding strips engaging over the meeting edges of the panels and ribs, the upper edge of the front finishing strip having notches receiving the lower ends of the ribs.

55 3. In a store counter, a longitudinally extending base rail, end rails, and spaced parallel transverse intermediate rails, transverse supporting frames seated on the intermediate 60 rails, finishing strips connected with the outer faces of the longitudinal and end rails and extending above the same forming in conjunction therewith seats, front and end panels fitted on the seats, the meeting edges of 65 the front panels engaging the front edges

of the transverse frames, and a shelf seated on the intermediate rails with the edges engaging the end and longitudinal rails and the rear edges of said panels.

4. In a store counter, a longitudinally extending rail, end rails and intermediate transverse rails, facing strips secured to the longitudinal and end rails and extending above the same defining seats in conjunction therewith, transverse supports seated on the intermediate rails including front and rear posts and top and intermediate strips, vertical ribs formed on the front faces of the front posts, end and front panels fitted on the seats, the adjacent edges of the front panels engaging the front faces of the posts and the opposite faces of the ribs, finishing molding strips arranged over the ribs and the adjacent edges of the front panels, a stock shelf fitted on the transverse rails and the end and longitudinal rails engaging the panels, supporting strips on the inner faces of the end panels in the same horizontal plane as the intermediate strips of the supports, a service shelf engaging the strips and panels, and a top fitted on the upper edges of the panels and the top strips of the supports.

5. In a store counter, a longitudinally extending rail, end rails and intermediate transverse rails, facing strips secured to the longitudinal and end rails and extending above the same defining seats in conjunction therewith, transverse supports seated on the intermediate rails including front and rear posts and top and intermediate strips, vertical ribs formed on the front faces of the front posts, end and front panels fitted on the seats, the adjacent edges of the front panels engaging the front faces of the posts and the opposite faces of the ribs, finishing molding strips arranged over the ribs and the adjacent edges of the front panels, a stock shelf fitted on the transverse rails and the end and longitudinal rails engaging the panels, supporting strips on the inner faces of the end panels in the same horizontal plane as the intermediate strips of the supports, a service shelf engaging the strips and panels, a top fitted on the upper edges of the panels and the top strips of the support, and a cornice extending above and below the top.

In testimony whereof I affix my signature.
LOUIS SCHUMM, III.
